UNITED STATES PATENT OFFICE.

RICHARD W. BURNETT, OF CHICAGO, ILLINOIS, ASSIGNOR TO CHARLES A. CARSCADIN,
OF CHICAGO, ILLINOIS.

COUPLING RELEASE-RIGGING.

1,283,657.

Specification of Letters Patent.

Patented Nov. 5, 1918.

Application filed February 11, 1916. Serial No. 77,621.

To all whom it may concern:

Be it known that I, RICHARD W. BURNETT, a citizen of the United States, residing at Chicago, in the county of Cook and State of Illinois, have invented a certain new and useful Improvement in Coupling Release-Rigging, of which the following is a full, clear, concise, and exact description, reference being had to the accompanying drawings, forming a part of this specification.

This invention relates to improvements in coupler release rigging.

Objects of this invention are to provide a release rigging for couplers which is composed of a minimum number of parts; which permits of a wide range of flexibility in the lateral and longitudinal movements of the coupler; and which is so arranged that the parts may be readily assembled and disassembled but when in operative position, the connecting member between the coupler lock and uncoupling rod cannot be accidentally or maliciously disconnected.

The invention furthermore consists in the improvements in the parts and devices and in the novel combinations of the parts and devices herein shown, described or claimed.

In the drawing forming a part of this specification, Figure 1 is a perspective view of a portion of the end of a freight car illustrating one embodiment of my invention. Fig. 2 is a vertical, sectional view, taken longitudinally of the car and at one side of the coupler. Fig. 3 is an end elevational view showing more particularly the connecting link between the coupler lock and uncoupling rod and the manner of attachment of said link to said other two members. And Fig. 4 is a detail horizontal sectional view taken substantially on the line 4-4 of Fig. 2.

In said drawing, 10 denotes the end sill of a freight car, 11 the buffer block or casting and 12 the coupler head provided as usual with the pivoted knuckle 13. The coupler is also provided with a coupler lock 14 of a well known form having an eye 15 at its upper end. A designates the uncoupling rod or lever, the same having a handle 16, horizontal portion 17 parallel with the end wall of the car, an outwardly and downwardly extending arm 18 located over the coupler head, said arm 18 at its outer end being provided with a substantially horizontally extending portion 19 arranged transversely to

the longitudinal center line of the car, said member 19 being provided with an end 20 which is bent so as to extend backwardly toward the end of the car and inclined downwardly from the horizontal when the uncoupling rod A is in normal position. The uncoupling rod A is rotatably mounted in suitable brackets 21 and 22 attached to the end of the car.

In order to operatively connect the rod or lever A with the coupler lock 14, I have provided an intermediate connecting link designated generally by the reference B. Said link B, as shown, is provided at its lower end with an eye 23, the plane of which is normally parallel with the end wall of the car, said eye being linked with the eye 15 of the coupler lock. Above the eye 23, the link B is provided with an elongated slot 24 within which is normally received the horizontal portion 19 of the uncoupling rod, the latter being adapted to work up and down in said slot 24, as will be apparent. As clearly appears from Figs. 3 and 4, the front or outer portion 25 of the link B is narrower than the widened flat back 26, or, stated in another manner, the general contour of the link B in horizontal section where it is engaged by the uncoupling rod is triangular for the purpose hereinafter specified.

In assembling the release rigging, the link B is first attached to the coupler lock 14 in the manner shown, after which the hook shaped inner end of the uncoupling rod A is threaded through the slot 24 of the link B. Finally the uncoupling rod A is attached to the car end by the brackets 21 and 22. After the parts are assembled, it will be obvious that the link B cannot slip accidentally around the corner or bend 27 in the uncoupling rod A, which is between the portions 19 and 20, since the wide back 26 of the link will effectively prevent this, which might otherwise be possible due to the connection between the link B and coupler lock 14 which permits the link B to angle or turn relatively to the lock about a vertical axis. In this way, I effectively prevent malicious or accidental disconnection of the link B and uncoupling rod so long as the latter is in proper position. At the same time, it will be noticed that the link B is permitted a wide range of movement laterally and can readily accommodate itself to the longitudinal and lateral movements of the coupler.

Furthermore, the lever arm 18 of the rod A is so disposed as to obtain maximum leverage in lifting the coupler lock. It will also be observed that the rod A may be formed 5 readily and cheaply from ordinary stock by simple bending operation to the desired form and also that the link B may be readily and cheaply manufactured.

I have herein shown and described what 10 I now consider the preferred embodiment of my invention but the same is merely illustrative, and I contemplate all changes and modifications that come within the scope of the claims appended hereto.

15 I claim:

1. In a coupler release rigging, the combination with an uncoupling rod having a substantially hook shaped end at its inner end, adjacent the coupler, of a slotted connecting link adapted to operatively connect 20 said lever with a coupler lock, said rod extending through the slot in said link and said link being wider on one side of the slot than on the other to thereby prevent the link

from passing accidentally around bends in 25 said uncoupling rod.

2. In a coupler release rigging, the combination with an uncoupling rod and a coupler lock having an eye at its upper end, of an intermediate connecting link between 30 said rod and lock said link having an eye at its lower end linked with the eye of said lock and slotted at its upper end, a portion of the uncoupling rod being extended through said slot and slidably therewithin, 35 the uncoupling rod being provided with shouldered portions therein at opposite sides of the link, and means preventing accidental disengagement of said link from the rod when the link and rod are assembled, said 40 means including a widened back wall on the link preventing the link from accidentally passing around said shouldered portions of the rod.

In witness that I claim the foregoing I 45 have hereunto subscribed my name this 31st day of January, 1916.

RICHARD W. BURNETT.
